FEED WATER HEATER

Johann Kolling, Oberhausen, Germany, assignor to The Babcock & Wilcox Company, New York, N. Y., a corporation of New Jersey

Application May 18, 1953, Serial No. 355,752

1 Claim. (Cl. 122—441)

The present invention relates to heat exchange apparatus, and more particularly to apparatus for heating feed liquid supplied to a vapor generator.

In the generation and superheating of a vapor, such as steam, it is customary to preheat the feed liquid before introduction into the circulatory system of the vapor generator. In the field of steam generation, feed water heaters, economizers and other heat exchange apparatus are customarily used. It has also been proposed that the feed water leaving the economizer section of a vapor generating unit would be passed through heat exchange tubes disposed in the steam space of the steam and water drum. Unfortunately, the use of such heat exchange elements in steam and water drums has necessitated the provision of special fittings for the indirect heater to avoid thermal stresses in the thick wall of the steam and water drum. Were such heat exchange elements to be located within the drum accessibility for maintenance and repair work would be hindered.

In the present invention the saturated steam produced by the steam generator is used, in part, to effect heating of the feed water. This is accomplished by indirect heat exchange means positioned externally adjacent the steam and water drum and connected therewith, with the steam condensate resulting from the heat exchange utilized as a source of spray cooling medium in a spray type superheated steam attemperator, or for other useful purposes.

The various features of novelty which characterize my invention are pointed out with particularity in the claim annexed to and forming a part of this specification. For a better understanding of the invention, its operating advantages and specific objects attained by its use, reference should be had to the accompanying drawings and descriptive matter in which I have illustrated and described an embodiment of my invention.

Of the drawings:

Fig. 1 is a side elevation, partly in section, of a steam generating unit incorporating the present invention, and

Fig. 2 is an enlarged view, partially in section, of a portion of the apparatus shown in Fig. 1, taken on the line 2—2 of Fig. 1.

As illustrated in the drawing, the present invention is applied to a steam generating unit of known type. However, it will be understood that the present invention is not limited to heat exchange in a steam generator but can be utilized in any type of vapor generating unit where a liquid is converted to a vapor by the application of heat to the liquid and the vapor.

In the illustrated embodiment of the invention, a known type of steam generator 10 is utilized to transfer the heat generated by the combustion of a granular solid fuel into water to produce superheated steam. The solid fuel is burned in cyclone type burners 11, such as disclosed in U. S. Patent 2,357,303. The cyclonic burners are water cooled by steam generating tubes in the walls thereof which are connected into the circulatory system of the steam generator. The products of combustion are delivered at high temperature by the cyclones 11 into an

2

upwardly elongated secondary combustion chamber 12 which is likewise enclosed by water cooled walls.

The products of combustion leaving the secondary combustion chamber pass over a plurality of superheating elements 13 positioned in the furnace outlet passageway 14. Thereafter, the partially cooled products of combustion are directed over the tubular elements of an economizer 15, and are passed to a stack (not shown) for discharge to the atmosphere. In many installations, the gases are passed through a combustion air heater before discharge to the atmosphere. Referring particularly to Fig. 1, feed or make up water from external feed water heaters and/or aerators are delivered to the inlet header 16 of the economizer 15. After passing through the economizer tubes, the feed water is delivered to an outlet header 17 and directed to the heating means of the present invention by a conduit 18.

As hereinafter described, the feed water passing through the conduit 18 enters the upper end of a large diameter downcomer 20 which is connected with one end of the steam and water drum 21 of the vapor generator, and discharges heated feed water to the lower header 22. At least two downcomers will be used in the circulatory system of the unit, but only one is shown in the drawings. The steam generated in the wall tubes of the cyclone furnaces 11 and of the secondary furnace 12 is delivered to the steam and water drum 21. Within the drum 21 the steam and water is separated by known means, such as shown in U. S. Patent 2,289,970 with a major portion of the steam passing through a plurality of saturated steam conduits 23 to a superheater inlet header 24. The saturated steam passes through the multiple loops of the first stage 25 of the superheater and is discharged to an outlet header 26. Thereafter, the superheated steam is passed through an attemperator 27 wherein the steam is cooled, as required, by spray attemperation with cooling water. The attemperated steam is thereafter delivered to an inlet header 28 of a second stage 29 of the superheater 13, with the superheated steam discharged from the loops thereof to an outlet header 30 and thence to a point or points of use.

As shown in Figs. 1 and 2, the downcomer 20 projects above the steam and water drum 21 an appreciable distance to provide a steam space 31 therein. Some of the saturated steam from the drum 21 passes through a row of conduits 32 to the upper end portion of the downcomer. The drum 21 is also connected with the downcomer 20 by means of a row of tubes 33 which open to the downcomer below the level of the drum 21. With both the steam and water spaces of the drum 21 connected with the downcomer 20, the water level within the drum will be substantially at the same level as the water level 34 in the downcomer.

The feed water delivered to the downcomer through the conduit 18 enters a distribution chamber 36 in the top of the downcomer which is separated from the steam space 31 by a tube sheet 37 and is in turn connected with the upper ends of and opens to a tube bundle 38 inserted in the upper end portion of the downcomer. The tubes in the tube bundle are preferably of small diameter to provide an extensive heat exchange area, and are thin walled since the pressure difference between the steam and water is slight.

The tubes of the tube bundle 38 are extended downwardly through the upper portion of the downcomer to a position spaced above the water level 34. A lower tube sheet or diaphragm 40 embraces the lower end portions of the tubes of the tube bundle at a position upwardly spaced from the discharge ends 41 of the tubes. The diaphragm 40 is provided with a cylindrical member 42 extending upwardly along the exterior side of tube bundle. The upper end of the cylinder is provided with a tube sheet 43,

through which the tube bundle extends, and an upwardly spaced domed condensate deflector member 44. The annular space 45 formed between the wall of the downcomer 20 and the cylinder member 42 provides a steam condensate collecting chamber for the condensate resulting from heat exchange between the saturated steam and the feed water passing through the tube bundle 38.

The condensate collecting in the annular space 45 is withdrawn through a pipe 46 by a pump 47 which discharges the condensate through a pipe 48 into the attemperator 27 for atomization in the form of a spray so as to control the temperature of the steam delivered by the superheater. It will be appreciated that the condensate collected in the annular space 45 of the downcomer 20 will be of a high degree of purity. It is within the scope of the present invention to utilize this relatively pure water for steam washing processes, as well as for attemperation of the superheater steam.

Under some conditions of operation the feed water added to the steam generation will not be sufficient to supply enough condensate through the pump 47 for steam attemperating purposes. Under such conditions additional water is supplied to the attemperator directly from the feed water supply. This is accomplished by admitting feed water into the pipe 48 through a branch pipe 50, with the flow therethrough regulated by a valve 51.

While it is recognized that the condensate will be at a pressure generally corresponding with the pressure within the steam and water drum, the pump 47 is provided to increase the pressure of the condensate for use in the atomization of the water for attemperating purposes.

It is within the contemplation of this invention to omit the diaphragm 40 and to discharge the condensate resulting from the heat exchange in the upper portion of the downcomer into the feed water.

In operation, the heated feed water passing from the economizer 15 is further heated in the upper portion of the downcomer 20 by heat exchange with saturated steam from the drum 21. The thus heated feed water passes directly to the downcomer circuit of the vapor generating

unit. The steam condensate obtained by the heat exchange in the downcomer is utilized as a source of spray liquid in the attemperator 26. Advantageously, the condensate is of high purity commensurate with the purity of the steam delivered to the superheaters.

While in accordance with the provisions of the statutes I have illustrated and described herein the best form and mode of operation of the invention now known to me, those skilled in the art will understand that changes may be made in the process without departing from the spirit of the invention covered by my claim, and that certain features of the invention may sometimes be used to advantage without a corresponding use of other features.

15 What is claimed is:

The combination with a steam generator having an upper steam and water confining drum, a multiple stage superheater receiving steam from said drum, said superheater having an interstage steam attemperator, said 20 steam generator having a circulatory system including at least one large diameter downcomer, the upper end portion of said downcomer extending above the steam and water drum of said steam generator, separate means connecting the steam and water spaces of said drum with said downcomer and forming a steam space within said downcomer, a plurality of tubular heat exchange elements positioned in the steam space of said downcomer, a diaphragm embracing the lower end of said tubular heat exchange elements in the steam space of said downcomer, means for passing feed water through said tubular elements to discharge into said downcomer, and means for 25 removing condensate from the steam space of said downcomer above said diaphragm and discharging said condensate into said steam attemperator.
